(57) **CLAIM**

The ornamental design for a solar-powered rechargeable battery as shown and described.

DESCRIPTION

FIG. 1 is a perspective view of a solar-powered rechargeable battery showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken lines through out the drawing figures depict portions of the solar-powered rechargeable battery that form no part of the claimed design.
